UNITED STATES PATENT OFFICE.

ALBERT H. BATES, OF CLEVELAND HEIGHTS, OHIO, ASSIGNOR TO THE AMERICAN MULTIGRAPH COMPANY, OF CLEVELAND, OHIO, A CORPORATION OF OHIO.

EMBOSSING MACHINE.

Application filed January 12, 1920. Serial No. 351,076.

To all whom it may concern:

Be it known that I, ALBERT H. BATES, a citizen of the United States, residing at Cleveland Heights, in the county of Cuyahoga and State of Ohio, have invented a certain new and useful Improvement in Embossing Machines, of which the following is a full, clear, and exact description, reference being had to the accompanying drawings.

This invention relates to a machine actuated by a keyboard and adapted to emboss letter and numeral characters on a strip of material adapted for use in an addressing machine. The machine is of that type wherein there are a pair of cooperating rotary die carriers, the position of which is dependent upon the key actuated, the particular dies thus placed being then caused to impress an interposed strip of material.

Reference is made to the following patents for a fuller showing and description of parts shown herein incidental to the die carrier, the dies and their immediate operating mechanism, namely, Patent #582,178, May 11, 1897, W. E. Crane, machine for producing printing purposes.

Patent #875,679, January 7, 1908, F. H. Alling, clutch for reliefographs.

30 Patents #883,399, and 883,401, March 31, 1908, R. Grieser, feeding mechanism for reliefographs, and carriage operating mechanism for reliefographs.

The present invention is concerned with 35 means for enabling the embossing to be effected in both upper and lower case characters, the patents mentioned operating only with single case characters. I accomplish the desired result without unduly increasing 40 the size of the machine, or the centrifugal force of the rotating parts, by means of a shift mechanism which enables the same general operating mechanism to actuate different sets of characters as desired.

45 Invention includes the shift feature broadly, and also a preferred way of carrying it out comprising so arranging the dies that they may have a shiftable movement in addition to their rotary-positioning and 50 radial-embossing movements. The invention comprises also the embodiment illustrated in the drawings hereof, and herein-after described in detail.

In the drawings Fig. 1 is a sectional side 55 elevation of the embossing machine; Fig. 2

is an enlarged sectional side elevation of the die carrier; Fig. 3 is an end view of the die carrier; Fig. 4 is a side elevation of part of the mechanism for shifting the dies; Fig. 5 is an enlarged detail of a portion of the die carriers adjacent to one of the dies with the die in one of its active positions; Fig. 6 is a perspective of one of the die blocks alone; Fig. 7 is a detail of a portion of the die carrier, being a part of the member secured to 60 the shaft; Fig. 8 is a perspective of a portion of the die shifting sleeve; Fig. 9 is a fragmentary rear elevation of the carrying member shown in Fig. 7; Fig. 10 is a perspective of a portion of the removable ring 65 which forms a part of the die carrier; Fig. 11 is an end view of the shifting mechanism shown in Fig. 4, being a vertical section on the line 11—11; Fig. 12 is a detail of a latch 70 which may be employed to hold the shift-key depressed; Fig. 13 is an end view of a latch shown in Fig. 12; Fig. 14 is a side elevation of another embodiment of my invention; Fig. 15 is an enlarged sectional elevation 75 of the die carriers; Fig. 16 is a fragmentary end view of the lower die carrier with its retaining ring removed. Fig. 17 is a cross section of the shiftable pivot block.

I will first describe the machine shown in 80 Fig. 1. This machine has a frame 1 in which are journaled a pair of parallel shafts 2 and 3, each of which has on it a disk-like die carrier 5. The dies hereinafter described of one die carrier are male dies, and those of the other die carrier are female dies and 85 substantially complementary thereto. The shafts 2 and 3 are geared together by gears 7 and 8 of the same size. Co-axial with the shaft 3 is a driving pulley 11 having a conical friction surface 12 against which bear 90 clutch shoes 13 connected with the shaft 3 in a manner to be hereinafter described. It thus results that the pulley may continuously rotate the two die carriers at the same speed but in opposite directions.

On the shaft 3 is a stop arm 20. At the rear of this stop arm and placed equidistantly about the axis of the shaft 3 are 95 a series of slides stop pins 21 guided in a suitable frame support 22 and each connected with one of the corresponding finger-keys 25. When a finger-key is depressed the corresponding pin is projected into the path of the stop arm, whereby the two shafts are 100 stopped with complementary die blocks fac- 110

ing each other. The arrangement of key levers, stop pins, stop arm, shafts and gears may for instance be of the form shown in the Alling patent mentioned.

5 Whenever the die carriers are stopped to present the die corresponding to the depressed key to each other, it is necessary that these dies be moved toward each other to impress an interposed plate. This mechanism as shown comprises single rotation clutch thrown into action automatically by the stoppage of the stop arm. This clutch is in the interior of the pulley 11. It has a driven shaft carrying a pair of eccentrics 30 which operate links 31 connected to oscillating arms 32 pivoted at 33. The forward ends of these arms push against plungers 35 and 36 which operate to shove upwardly the topmost die in the lower carrier 5 and 20 shove downwardly the lowermost die in the upper carrier 5, thus effecting the embossing operation on an intermediate plate.

The means by which the stoppage of the stop arm throws into action the single rotation clutch is immaterial to the present invention. It may be of the form shown in the patent of Alling where the stop arm has a hub 40 bearing a cam face coaxing with a complementary cam face on a sleeve 41 surrounding the shaft and connected with spring arms carrying the driving clutch shoes 13 and adapted to move longitudinally to actuate the normally-idle single-rotation internal clutch connected with the eccentrics.

35 With such mechanism as just mentioned when a key is depressed and pin projected, the stop arm engaging such pin stops the two carriers and stops the hub 40; the frictional drive however continues to carry forward 40 the sleeve 41 which by reason of the cam connection moves longitudinally against the action of a spring. In such longitudinal movement it throws into engagement the internal clutch which connects the shaft carrying the eccentrics with the driving pulley. This clutch may be of the type shown in the Alling patent or may be some other type of single-rotation clutch. When this clutch is 45 thrown into engagement the eccentric shaft makes a single rotation, and this movement shoves the plungers inwardly and then withdraws them, the clutch automatically disengaging itself at the end of a single rotation.

55 The mechanism so far described is not specifically a part of my invention and may be varied as desired. The important characteristics of this mechanism, as far as my invention is concerned, is that the depression of a key causes stopping of the rotary die carriers with the complementary corresponding die blocks facing each other, and then automatically operates the plungers to project the die blocks to effect the embossing.

60 Some suitable means is preferably em-

ployed to position the plate to be embossed between the die carriers and to feed such plate step by step following each impression to bring it into position for receiving the next letter. I have shown in the drawing at 50 a device for positioning the plate; this device guiding the plates one after another from a hopper and causing them to drop around the guide and pass between the die carriers; then mechanism of the device shifts the plate in a fore-and-aft direction as the embossing takes place. Such plate-holding and feeding mechanism is illustrated in the two patents to Grieser mentioned and need not be further described.

70 As heretofore stated, my invention is concerned with the provisions enabling upper and lower case characters to be embossed. To effect this without making the machine complicated or bulky or unduly increasing the centrifugal force of the die carriers, I provide dies having both upper and lower case characters and I arrange suitable shift mechanism so that either set of characters may cooperate with the plunger mechanism, 80 this shift mechanism being actuated by a shift key in or adjacent to the keyboard.

85 The double case operation may be effected in several different ways, all falling in their broad aspects within the scope of this invention, the object to be obtained being to provide the necessary number of characters without materially increasing the diameter of the carrier members. However, in the embodiment illustrated, I effect the result 95 by providing each die block with two characters and by shifting the die blocks in their carriers to present the upper or lower case as desired. I will now describe this specific embodiment:

100 The die carrier 5 as shown, has a disk-like head 60 having a hub 61 secured to the corresponding shaft. In this head are radial passages 62 occupied by the die blocks 70 (Fig. 7). The head carries short studs 63 110 projecting into the passages 62, and the die blocks, for flaring grooves 71 in their sides into which these studs project. The upper ends of the grooves serve in the inner or normal position of the blocks to pivot 115 them to the carrier. The die blocks have characters 73 and 74 on their faces, positioned at such an angle to each other that when one is in active position the other is 120 swung clear of the plate to be embossed. The blocks have guiding edges 75 and 76 shaped to engage the corresponding walls on the carrier and guide the blocks effectively in their radial movement, the forward edge 75 being engaged in one position and the 125 rearward edge 76 being engaged in the other position. The blocks are normally held in their innermost or inactive position by individual springs 80 anchored at 81 to a disc 82 rigid on the shaft. These springs extend 130

through slots 65 in the carrier and engage notches 78 in the die blocks.

A convenient way to construct the carrier is to make the radial grooves partly in the portion 60, 61 connected with the shaft and partly in a ring 66 secured thereto. The studs 63 may be pins resting in notches 67 in the meeting faces of these two members of the die carrier. Each member of the die carrier will preferably have the radial grooves milled in it, and the transverse notches made by a circumferential groove crossing all of the ribs left between the radial grooves; the pins are then placed in these notches with their ends projecting into the adjacent grooves, and then the other member 66 is put in place and secured by screws 68. I thus make a rigid unit having the characteristics of radial passages open at the outer and inner periphery, short studs projecting into the passages from opposite sides, and slots through the rear wall of the member to the passageways. The details of this die carrier are clearly shown in Figs. 7, 9 and 10.

Surrounding each die carrier 5 is a sleeve 100 having slots 101 through which the dies project. This sleeve has a hub 103 embracing the shaft. In the outer face of this hub is a radial groove 103. This groove furnishes means whereby the sleeve may be engaged to be shifted longitudinally and thus swing all of the dies into one active position or the other. Irrespective of which position the dies have, they are operable by the plunger 35 or 36.

The mechanism for engaging and longitudinally moving the sleeves 100 to shift the dies is best shown in Figs. 4 and 11. As there shown it consists of a yoke 110 slidably mounted on stationary guiding studs 111 and having forks 112 and 113 engaging the grooves 103 of the sleeves. This yoke has pins 115 to which is pivoted the upper arm 45 of the rock arm 116 on the rock shaft 117. A substantially horizontal arm 118 on this rock shaft is connected by a link 119 with the shift lever 120. A suitable spring 128 tends to elevate this shift lever and thereby maintain both sleeves in one extreme position, which is preferably that where the lower case characters are active. When the key is depressed it pulls downwardly on the link 119 and swings the bell crank to shift 55 the yoke and the two sleeves 100 rearwardly to swing all the dies to bring their other set of characters, preferably the upper case, into active position.

It is convenient to have suitable means 60 to hold the shift lever depressed. For this purpose I have shown a catch 121 pivoted to the machine frame and having an eccentric or cam foot 122 adapted to extend across and engage the shift lever and hold it depressed, this shift lever being guided by a

frame slot 123. This catch has an arm which is normally held in either extreme position by means of its engagement with a leaf spring 126 carried by the frame and having a slight intermediate hump which 70 the lever must pass across in moving from one extreme position to the other. This catch mechanism is shown in Figs. 12 and 13.

It will be seen that by my invention I have adapted an embossing machine of the 75 type mentioned, to an operation with two sets of characters without adding much mechanism to the machine and without materially increasing its size and weight and without troublesome increase in the centrifugal force of the rotating die carriers.

It is to be understood that many changes and modifications may be made in the mechanism shown for accomplishing the desired results, and I do not wish to be limited to 85 the particular mechanism except where the claims distinctly so specify. For instance, in place of the die carrying arrangement herein illustrated there may be an arrangement of two rotary carriers axially aligned 90 on each shaft and facing each other on opposite sides of the plunger. Such a device is shown and specifically claimed in my co-pending application, Serial No. 357,888, filed February 11, 1920, though in its 95 broader aspects it comes within the scope of this invention.

Another means for accomplishing the result, and intended to be covered broadly by claims in this patent, consists as shown in 100 Figs. 14 to 16 in using for the lower case characters, a rotary wheel 130 having die blocks 131 sliding radially only, substantially as shown in Patent 883,400 issued March 31, 1908, to R. Grieser for a die carrier, and forming the upper case characters on spring fingers 132 which extend longitudinally in a cylindrical course and may be carried by a suitable disk-like head as 105 shown in Patent 859,214 granted July 9, 1907, to R. Grieser for a die carrier or may be made longitudinally slitting a spring metal sleeve 133 as shown also in patents to Crane and Alling, already mentioned. In either case the spring fingers are arranged 110 in the form of a cup or ring of slightly larger diameter than the carrier for the small-letters, which cup or ring may be shifted longitudinally as a unit over the small-letter carrier, so that when the small-letter dies are plunged outwardly they will 115 engage the inner surface of the spring fingers and shove them outwardly to effect the embossing. In this embodiment sufficient clearance is provided between the male 120 and female lower case carriers to provide for the surmounting of the spring fingers, and the plunging stroke is increased when the surmounting fingers are not active to compensate therefor. This increase in stroke 125

130

may be readily effected by shifting the pivots of the oscillating arms operating the plungers, this shifting being caused by the same shift-key mechanism which shifts the

5 supplementary upper case dies into and out of active position, for instance by means of the linkage 135 and 136 and the slidable pivot blocks 137 and 138.

It will be seen that the two alternative 10 embodiments above described and illustrated in common with the embodiment illustrated in my co-pending application above mentioned have the characteristic of two sets of dies for upper and lower case respectively, carried by a single shaft and operated by a common plunger mechanism and brought to and from active position by a shift key operating mechanism. All such embodiments are intended to be covered in 15 the claims hereof.

I claim:

1. The combination with two sets of male dies and two sets of female dies cooperative therewith, of a carrier for said dies and 25 means operable independently of the carrier for rendering active either cooperative set of male and female dies.

2. The combination of an upper case set 30 of embossing dies, a lower case set of embossing dies, means for holding a plate to be embossed, and shift mechanism for causing the mutual presentation of the plate and either set of dies as desired, whereby the impression obtained with the dies of either 35 set occurs at the same relative position on the plate.

3. In an embossing machine, the combination with means for carrying and operating 40 cooperating complementary dies, means for holding an address plate between them, key-board control mechanism for said dies and a shift mechanism associated with the key-board control mechanism for causing cooperation between the plate and a different 45 set of die characters.

4. In an embossing machine, the combination with means for carrying and operating 50 cooperating complementary character dies, of a shift mechanism cooperating with said means for causing a different set of characters to act on the article being embossed.

5. In an embossing machine, the combination with means for carrying and operating 55 cooperating complementary letter dies, of a shift mechanism associated with said means for changing from upper to lower case and vice versa.

6. The combination with cooperative 60 rotary die carriers, of dies carried thereby arranged in two related sets, and a shift mechanism cooperating with said carriers for causing either set to be active.

7. The combination with a rotary die carriers of male and female upper case dies and

male and female lower case dies carried thereby, and mechanism associated with said carriers for changing from one case to the other.

8. The combination of rotary die carriers 70 having male and female dies, keyboard actuated stopping mechanism for the carriers, and shifting mechanism operable independently of the stopping mechanism to change the character of impression. 75

9. The combination of rotary die carriers having male and female dies, means for rotating the carriers, keyboard actuated stopping mechanism for the carriers, and shift key actuated shifting mechanism operable so simultaneously on said dies to change the character of impression.

10. The combination of rotary die carriers two sets of male dies and two sets of female dies carried thereby, means for rotating the 85 carriers, means for stopping the rotation, keyboard mechanism for actuating the last mentioned means, shifting mechanism co-operating with the dies to change the presentation of the article to be impressed from 90 one set of male and female dies to the other set, and means for operating the shifting mechanism.

11. The combination of rotary die carriers, a shaft for each carrier, means for rotating the same, keyboard mechanism for stopping the die carriers with cooperating 95 dies facing each other, said dies presenting two sets of characters, and shift mechanism associated with said shafts for rendering one 100 set active and the other inactive with reference to the article to be impressed.

12. The combination of rotary die carriers, means for continuously rotating them, means for stopping the rotation, keyboard 105 mechanism for actuating the last mentioned means, shifting mechanism operable independently of the stopping means to cause different sets of dies to be presented to the article to be impressed, and means for operating the shifting mechanism. 110

13. The combination of rotary die carriers, means for continuously rotating them, means for stopping the rotation, keyboard mechanism for actuating the last mentioned 115 means, means for giving the dies their embossing movement consequent upon the stoppage of the rotation, shifting mechanism to cause different sets of dies to be presented to the article being impressed, and means 120 for operating the shifting mechanism.

14. The combination with die carriers, of keyboard controlled positioning mechanism, therefor automatically operating means for giving the positioned dies their embossing 125 movement when stopped, and shift mechanism for giving the dies another movement to change the case of the characters which are active.

15. The combination with rotary die car- 130

- riers, means for rotating them, keyboard mechanism for stopping their rotation, automatically actuated mechanism for giving the positioned dies their embossing movement, when stopped, and means for giving the dies a movement other than their positioning or embossing movement to change from upper to lower case and vice versa.
16. The combination with rotary die carriers, an upper case set of male and female dies and a lower case set of male and female dies carried thereby, means for rotating the carriers, keyboard mechanism for stopping their rotation, automatically actuated mechanism for moving into cooperation male and female dies which face each other, when stopped, and means for giving the dies a movement other than their positioning or embossing movement to change the presentation from upper to lower case and vice versa.
17. The combination with rotary die carriers, radially movable dies carried thereby, means for rotating them, keyboard mechanism for stopping them in the rotation, automatically actuated mechanism for moving radially dies which face each other, when stopped, and means for giving the dies a movement other than their positioning or embossing movements to change from upper to lower case and vice versa.
18. The combination of two sets of dies, each set including a series of male dies and a cooperating series of female dies, carriers for said dies, shift mechanism associated with said carriers for determining which set is active, and mechanism common to the two sets adapted to operate either set.
19. The combination of two sets of dies, each set including a series of male dies and a cooperating series of female dies, keyboard mechanism for positioning them, shift mechanism associated with the keyboard mechanism for determining which set is active, and mechanism common to the two sets adapted to operate either set.
20. The combination with a frame of a plurality of sets of dies carried thereby, each set including a series of male dies and a cooperating series of female dies, shift mechanism carried by the frame for determining which set is active, rotary carriers for said dies, keyboard mechanism for positioning the carriers, and mechanism common to the two sets adapted to operate either set, said mechanism being operated automatically consequent upon the dies selected by the keys being positioned.
21. The combination of rotary die carriers, mechanism for continuously rotating them, keyboard controlled mechanism for stopping the die carriers, mechanism for operating individual dies when stopped in position, a single rotation clutch operating the last mentioned mechanism and actuated by the stopping of the carriers, and shift mechanism to enable either of two sets of die characters to be active.
22. The combination of rotary die carriers, two sets of male dies and two sets of female dies carried thereby, mechanism for continuously rotating the carriers and keyboard controlled mechanism for stopping the carriers, mechanism for operating the individual dies, a single rotation clutch operating the last mentioned mechanism and actuated by the stopping of the carriers and key actuated shift mechanism to enable either of two sets of characters to be active.
23. The combination of a pair of rotary die carriers, means for continuously rotating them, keyboard controlled mechanism for stopping the rotation, automatic mechanism actuated by such stopping to cause the dies which face each other to impress an intermediate plate, and means for shifting the die members to present different sets of characters, as desired.
24. The combination of a pair of rotary die carriers, each having radially movable die blocks, means for continuously rotating the carriers, keyboard controlled mechanism for stopping the rotation, automatic mechanism actuated by such stopping to move radially outward the dies which face each other to impress an intermediate plate, and means for shifting the dies to present different sets of characters, as desired.
25. The combination of a pair of rotary die carriers, each having radially movable die blocks, each die block having an upper case and a lower case character, the dies in one carrier being male and those in the other female, means for continuously rotating the carriers, keyboard controlled mechanism for stopping the rotation, automatic mechanism actuated by such stopping to cause the dies which face each other to impress an intermediate plate, and means for shifting the dies to present upper or lower case faces as desired.
26. The combination of a rotary die carrier, the die members therein each having two faces, means for continuously rotating the carrier, keyboard controlled mechanism for stopping the rotation, automatic mechanism actuated by such stopping to cause a die to effect an impression, and means for simultaneously shifting all the dies in the carrier to change from one embossing face to another.
27. The combination of a pair of rotary die carriers, each having dies with a plurality of faces, means for rotating them, mechanism for stopping the rotation, mechanism to cause the dies which face each other to impress an intermediate plate, and means for simultaneously shifting all the dies in the two carriers to change from one embossing face to another.

28. The combination of a pair of rotary die carriers, male die blocks in one carrier and female die blocks in the other, each die block having both an upper case and a lower case die, means for continuously rotating the carriers, keyboard controlled mechanism for stopping the rotation, automatic mechanism actuated by such stopping to cause the dies which face each other to impress an intermediate plate, and means for simultaneously shifting all the dies in the two carriers to change from one embossing face to the other.
29. The combination of a rotary die carrier having individual die members each with a plurality of characters, mechanism for shifting the members in their carriers to change from one face to another, mechanism for moving the carrier to position a die member, and means for moving the die member in the carrier to effect the impression.
30. The combination of a rotary die carrier having individual die blocks which are movable, each block having a plurality of characters, mechanism for shifting the blocks in their carrier to change from one face to another, and mechanism for moving the blocks radially in their carrier to effect an impression.
31. The combination of a pair of rotary die carriers, each having individual die blocks which are movable, each block having a plurality of characters, the characters on one carrier being male characters and those on the other being female characters, mechanism for shifting the blocks in their carriers to change from one face to another, and mechanism for moving the blocks radially in their carriers to effect the impression.
32. The combination of a rotary die carrier, individually movable die members carried thereby, each having a plurality of faces, means for rotating the carrier to position the die members, and means for moving the positioned member longitudinally of the axis of rotation to select the face with which to emboss.
33. The combination of a rotary die carrier, individually movable die members carried thereby, each having a plurality of faces, means for rotating the carrier, keyboard controlled mechanism for stopping the rotation to position a die member correspondingly to the key actuated, and means for moving the positioned member longitudinally of the axis of rotation to select the face with which to emboss.
34. The combination of a rotary die carrier, individually moveable die members carried thereby each having a plurality of faces, means for rotating the carrier to position the die members, means for moving the positioned member longitudinally of the axis of rotation to select the face with which to emboss, and means for moving the positioned die radially to effect the embossing.
35. The combination of a rotary die carrier, individually movable die members carried thereby each having a plurality of faces, means for rotating the carrier, keyboard controlled mechanism for stopping the rotation to position a die member correspondingly to the key actuated, means for moving the positioned member longitudinally of the axis of rotation to select the face with which to emboss, and means operating automatically consequent upon the positioning of the die member for moving it radially to effect the embossing.
36. In an embossing machine, the combination of a rotary die carrier, dies therein, each having a plurality of characters, and means for rocking the dies to change the character presented.
37. In an embossing machine, the combination of a movable die carrier, dies pivotally and slidably mounted therein, each having a plurality of characters, means for rocking the dies to change the character presented, and means for moving the rocked dies to effect the embossing.
38. In an embossing machine, the combination of a rotary die carrier, dies therein, each having a plurality of characters, means for rocking the dies transversely to change the characters presented, and means for moving the dies radially to effect the impression.
39. In an embossing machine, the combination of a rotary die carrier, dies therein, each having a plurality of characters, means for rocking the dies transversely to change the character presented, means for rotating the carrier, keyboard mechanism for stopping the rotation, and automatic mechanism for moving the dies radially to effect the impression.
40. In an embossing machine, the combination of a rotary die carrier, dies therein, each having a plurality of characters, a sleeve surrounding the die carrier and having openings through which the dies project, and means for shifting the sleeve longitudinally.
41. In an embossing machine, the combination of a rotary die carrier, dies pivotally and slidably mounted therein, each having a plurality of characters, a sleeve surrounding the die carrier and having openings through which the dies project, means for shifting the sleeve longitudinally to rock the dies to change the character presented, and means for moving the selected die radially to effect the impression.
42. The combination of a pair of rotary die carriers, each carrier having movable dies, each die having a plurality of characters, the dies of one carrier being male, those of the other carrier being female, said dies being pivotally as well as slidably connected with their carriers, means for ro-

tating the die carriers to position a die in each, means for moving the set of dies in their pivots, and means for moving radially the dies which face each other in the two carriers.

43. The combination of a pair of rotary die carriers, each carrier having radial slots, dies in said slots, each die having a plurality of characters, the dies of one carrier being male, those of the other carrier being female, said dies being pivotally as well as slidably connected with their carriers, means for rotating the die carriers, means for stopping the rotation, means for rocking the set of dies in their pivots, and means for moving radially the dies which face each other in the two carriers.

44. The combination of a pair of rotary die carriers, each carrier having radial slots, dies in said slots, each die having a plurality of characters, the dies of one carrier being male, those of the other carrier being female, said dies being pivotally as well as slidably connected with their carriers, means for continuously rotating the die carriers, keyboard controlled means for stopping the rotation, means for rocking the set of dies in their pivots, a shift key for controlling the last mentioned means, and means operated automatically consequent upon the stopping of the rotation of the carriers for moving radially the selected dies in the two carriers.

45. The combination of a pair of rotary die carriers, each carrier having dies, each die having a plurality of characters, the dies of one carrier being male, those of the other carrier being female, said dies being pivot-

ally as well as slidably connected with their carriers, means for continuously rotating the die carriers, keyboard mechanism controlling the stopping of the carriers, a single rotation clutch automatically actuated by such stopping for moving radially the positioned dies, and a manually operated shift lever for simultaneously rocking the various dies in the two carriers.

46. The combination of a pair of rotary die carriers, each carrier having radial slots, dies in said slots, each die having a plurality of characters, the dies of one carrier being male, those of the other carrier being female, said dies being pivotally as well as slidably connected with their carriers, means for rotating the die carriers, means for stopping the rotation, a movable sleeve surrounding each carrier and having openings through which the dies project, means for moving radially the dies in the two carriers which face each other, keyboard mechanism controlling the stopping of the carriers, a single rotation clutch automatically actuated by such stopping for operating the radially moving mechanism, and a manually operated shift lever and mechanism controlled thereby for simultaneously shifting the two sleeves.

47. In an embossing machine, the characteristic of two sets of dies for upper and lower case respectively, carried by a single shaft and operated by a common plunger mechanism and brought to and from active position by a shift key operating mechanism.

In testimony whereof, I hereunto affix my signature.

ALBERT H. BATES.
